UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed March 8, 1921. Serial No. 450,745.

To all whom it may concern:

Be it known that I, FRED S. CARR, a citizen of the United States, and a resident of Newton, in the county of Middlesex and 5 Commonwealth of Massachusetts, have invented an Improvement in Fasteners, of which the following description, in connection with the accompanying drawings, is a specification, like characters on the drawings 10 representing like parts.

This invention pertains to improvements in separable fasteners. It is among the objects of the invention to provide a separable fastener of simple construction and superior 15 holding power.

Referring to the drawings, which show a preferred embodiment of one illustrative form of my invention:

Figure 1 is a front elevation of two pieces 20 of fabric connected by the preferred form of fastener;

Fig. 2 is a section on the line 2—2 of Fig. 1;

Fig. 3 is a section on the line 3—3 of 25 Fig. 2;

Fig. 4 is an elevation of the preferred form of socket member prior to attachment thereof to its carrying fabric;

Fig. 5 is a diagrammatic view showing 30 the preferred form of socket member and its attaching part in their relation relative to each other and to the socket-carrying fabric prior to assembly; and

Fig. 6 is an elevation of the socket member illustrated in Fig. 4 taken from the opposite side thereof.

Referring to the drawings and to the preferred form of my invention selected for illustrative purposes, I have shown in Fig. 2 40 a stud including a head 7, a neck 8 and a base portion 9 secured to the stud-carrying fabric 10 by a stud-securing rivet 11. The preferred form of socket illustrated is peculiarly well adapted for being metallically 45 fastened to the socket-carrying fabric 12. Where this form of attachment is utilized, I may provide a plate 13, having a stud-receiving aperture therethrough and containing a spring 14, with a flanged side wall 15 flanged inwardly at 16 to engage and retain 50 a socket-securing part which preferably includes, as illustrated, the plate portion 17 adapted to overlie portions of the spring 14, more fully hereinafter described, and including 55 a tubular projection 18 from which

prongs 19 project adapted to penetrate the stud-carrying fabric 12 and to be clenched within securing means on the opposite side of the socket-carrying fabric from the socket proper. The securing means may be of 60 any suitable form, but preferably includes an anvil portion 20 for turning the prongs 19, and a clenching portion 21 adapted to be pressed against the socket carrying fabric 12 by the prongs 19 when turned. Where 65 the clenching portion and anvil portion are separate, as illustrated, they may be held together by a cap 22 providing a finished appearance for the outside of the fastening. Between the anvil portion and the clenching 70 portion is preferably provided a space into which the socket-carrying fabric 12 may be crowded by the flange 18 underlying the prongs 19, as shown in Fig. 2. The prongs 19 are preferably pointed, as illustrated, 75 and are preferably spaced apart at a considerable distance (Fig. 5) so that they may to an inconsiderable degree only cut the socket-carrying fabric, leaving wide portions thereof uncut or unpenetrated and adapted 80 to be engaged by the outer face of the flange 18, thereby providing a very secure fastening of the socket to its carrying fabric.

The casing 13 is provided with a stud-receiving aperture, as before stated, and 85 this stud-receiving aperture is preferably notched as at 30 (Fig. 6) at that side thereof which comes in the line of strain between stud and socket, this usually being at that side thereof adjacent the margin of the socket-carrying fabric. The notch 30 is preferably of such proportions as to provide a locking against separation of the stud from the socket by the resolution of forces arising 90 from lateral strain between stud and socket 95 while permitting, even under a considerable degree of lateral strain, separation of stud and socket pursuant to a strain in a direction more nearly axial than that arising from the resolution of forces under lateral 100 strain. The stud-receiving aperture 31 is preferably intersected by a plurality of resilient jaws, preferably integral with the spring 14 and preferably so formed as to press the neck of the stud toward the 105 notch 30. To provide a maximum resiliency for these jaws, the spring 14 is preferably of the W-shape illustrated, the central portion 32 may extend to or near the periphery of the interior of the socket and 110

rotation of the spring 14 relative to its casing may be prevented in any suitable way, as by an indentation 33 from the casing extending between the opposite sides of the 5 spring. The offsets 34 and 35, where the spring intersects the stud-receiving aperture, are effective to press the stud toward the notch 30, and the return bends 36 and 37, free to move laterally between the opposite 10 sides of the casing, increase the resiliency of the spring. This resiliency may be further increased by additional return bends 38 and 39, spaced from the interior wall of the casing, while the ends 40 and 41 of the 15 spring may rest against this interior wall.

To reinforce the plate 13 adjacent the stud-receiving aperture therein, and also to promote easy separation of stud and socket when under lateral strain, the plate 13 may 20 be and preferably is, as indicated, turned back adjacent the periphery of the stud-receiving aperture to provide a bead 50, thus doubling the effective thickness of the plate adjacent the stud-receiving aperture. This 25 also preferably provides a rounded edge surrounding the stud-receiving aperture so that separation of stud and socket is facilitated by reduction of the friction which might otherwise exist between a relatively 30 short and rough edge on the plate and the neck of the stud. The bead 50, in the preferred form of my invention, is formed prior to the punching of the notch 30, so that the bead will not extend around the notched 35 portion of the socket plate. In the preferred form of my invention, the notch 30 is of somewhat less width, where it joins the main stud-receiving aperture, than the diameter of the neck of the stud, thus preventing a 40 complete entrance of the neck of the stud into the notch and insuring a bearing between the points at each side of the notch and the neck of the stud. The preferred construction illustrated greatly increases 45 the strength of these points for any given gauge of metal used in forming the socket plate and makes the plate of greater effective thickness adjacent the stud-receiving aperture at one side thereof than at the 50 other side thereof.

The provision of the bead 50 may be of use in other types of socket, and I have claimed it broadly in a copending application filed herewith, Serial No. 450,748.

55 While I have shown and described a preferred form of one embodiment of my invention, it will be understood that changes involving omission, substitution, alteration and reversal of parts, and even changes in 60 the mode of operation, may be made without departing from the scope of my invention, which is best defined in the following claims.

Claims.

65 1. A socket for separable fasteners in-

cluding a casing having a plate with a stud-receiving aperture therethrough, said plate having a return flange at its edge adjacent the aperture, and said plate notched to provide an extension of said aperture. 70

2. A socket for separable fasteners including a casing having a plate with a stud-receiving aperture therethrough, said plate having a return flange at its edge adjacent the aperture, and said plate notched to provide an extension of said aperture, the marginal portion of said plate adjacent said notch comprising a single thickness only of the plate. 75

3. A socket for separable fasteners comprising a casing having a stud-receiving aperture therein and a notch communicating with said aperture, said casing reinforced by a bead around the margin of said aperture, said bead projecting inwardly of said casing to provide a relatively smooth rounded edge about said aperture on the sides thereof away from the notch. 80

4. A socket for separable fasteners comprising, in combination, a casing having a tubular flange projecting from its rear side, spaced apart prongs projecting from the end of said flange, securing means on the opposite side of the socket-carrying fabric, said securing means presenting an anvil portion for turning said prongs, a clenching portion to be pressed toward the fabric by said prongs when turned, and a space between said anvil portion and said clenching portion, said space opposite said tubular flange to permit the carrying fabric to be 90 pressed thereinto by said flange. 95

5. A socket for separable fasteners including a casing having a flange projecting from one side thereof, and fabric-piercing prongs projecting from the flange in the same direction, said prongs spaced apart from each other; in combination with an anvil member having a space to receive and means to turn and clench all of said prongs, so that the edge of the flange between the prongs is brought by the clenching operation against the fabric which the prongs pierce and said edge presses the fabric into the space provided by the anvil member. 105 110

6. A socket for separable fasteners comprising, in combination, a casing part providing a plate having a stud-receiving aperture therein, a second casing part secured to said first casing part, a spring between said casing parts, said second casing part having a plurality of spaced apart fabric-piercing prongs projecting therefrom, and securing means for application to the opposite side of the socket-carrying fabric from said casing parts, said securing means including prong-turning anvil means and prong-engaging clenching means engaged by said prongs when turned and pressed by said prongs toward the carrying fabric and said 120 125 130

casing parts on the opposite side of said fabric.

7. A socket for separable fasteners comprising, in combination, a casing part providing a plate having a stud-receiving aperture therein, a second casing part secured to said first casing part, a spring between said casing parts, said second casing part having a plurality of spaced apart fabric-
10 piercing prongs projecting therefrom, said prongs rising from a projecting flange surrounding a central aperture in said second

casing part, and securing means for application to the opposite side of the socket-carrying fabric from said casing parts, said 15 securing means including prong-turning anvil means and separate prong-engaging clenching means engaged by said prongs when turned and pressed by said prongs toward the carrying fabric and said casing 20 parts on the opposite side of said fabric.

In testimony whereof, I have signed my name to this specification.

FRED S. CARR.
